ELECTRICALLY HEATED DUTCH OVEN

Raymond N. Sellon, Jr., Milwaukee, Wis., assignor
to Geuder, Paeschke & Frey Co., Milwaukee,
Wis., a corporation of Wisconsin

Application April 8, 1950, Serial No. 9,053

Term of patent 7 years

(Cl. D81—10)

To all whom it may concern:

Be it known that I, Raymond N. Sellon, Jr., a citizen of the United States, residing at Milwaukee, in the county of Milwaukee and State of Wisconsin, have invented a new, original, and ornamental Design for an Electrically Heated Dutch Oven, of which the following is a specification, reference being had to the accompanying drawing, forming a part thereof, and in which is shown a perspective view of a Dutch oven embodying my new design. Except for the control device shown at the left in the drawing, the side of the Dutch oven not shown in the drawing is like the side shown.

I claim:

The ornamental design for an electrically heated Dutch oven, substantially as shown and described.
